UNITED STATES PATENT OFFICE

DICKBAN M. SARKISIAN, OF FOREST HILLS, NEW YORK

DRAPERY AND HEADING HOOK

Application filed May 22, 1928. Serial No. 279,647.

The invention relates generally to drapery hanging devices, and more especially to a hook member adapted to be secured directly to the drapery. It has for its object a novel hook member which may be quickly and conveniently applied to the drapery and may as readily be removed therefrom, the invention contemplating a hook member which requires no sewing or like operation in the attachment thereof.

To this end, the invention comprises a hook device with sharpened point or prong which will readily penetrate the material composing the drapery and which hook member may be manipulated that it may be positioned in said drapery in manner to prevent normally its dislodgment therefrom, said hook member, furthermore, being adapted to fit over or into drapery-supporting devices as curtain rings and the like, slideable, for example, along a curtain rod.

The nature of the invention, however, will best be understood when described in connection with the accompanying drawings, in which:

Figs. 1, 2 and 3 illustrate various forms of the novel heading hooks; and Figs. 4 and 5 are transverse sections thereof taken on the lines 4—4 and 5—5, Figs. 1 and 2 respectively.

Figs. 6 and 7 are respectively a side and front elevation of a simplified form of the hook or drapery pin; and Fig. 8 is a vertical section therethrough taken on the line 8—8, Fig. 6 of the drawings, and looking in the direction of the arrows.

Figs. 9 and 10 are, respectively, side and front elevations of a modification in the simplified form of hook.

Figs. 11 and 12 are, respectively, a front elevation and plan of a form of hook member of the type illustrated in Figs. 1 to 3 and adapted for mounting directly upon a rod or the like.

Fig. 13 is a perspective rear view of the upper portion of a curtain and illustrates the manner of suspending the same from a curtain rod by means of the novel heading hook, more especially of the nature shown in Figs. 5; while Fig. 14 is a similar view illustrating the manner of attaching the curtain by

means of the simplified form of hook of the nature shown in Figs. 6—10, inclusive.

Referring to the drawings, the hook illustrated in Figs. 1—5 is of a type more especially adapted for supporting a stiffened heading of a curtain or the like, and comprises a length of more or less resilient wire 10 bent at its opposite ends, for example, to form the two hook portions 11 and 12, respectively. The latter are designed to pass freely through the curtain or like member to be suspended, as through the inner wall of the heading 15 thereof, Fig. 13 of the drawings, and to be brought back again to the outer surface, as indicated. The included cloth material 55 pockets then more or less within the circular section of a hook portion; and dislodgment or loosening may be more or less obviated by a turned or bent-in portion affording slightly constricted throats 16 and 17 of the respective hooks. 60

To mount the aforesaid heading hook on a rod or like member, for example on the curtain rod 20, rings 21 may be provided to slide along said rod in the usual manner and having eyes 22 carried thereby which are adapted to receive a down-turned extension or hook 23 of the novel hook member. This latter element may be mounted on the length 10 in any suitable manner, for example as indicated in Figs. 1 and 4, by means of a clamping slug or block or like member 25 designed to receive corresponding bent portions or lateral bulges 26 and 27 respectively of the wire length 10 and hook extensions 23. 70

As indicated in Figs. 2 and 5, the hook extension 23' is itself provided with a clamping inner portion 28 fitting over the bent portion 29 of the wire length 10; while as shown in Fig. 3, the inner end of the hook extension portion 30 is continued and twisted about a portion of the length 10 of the heading hook member proper. 80

Figs. 6—8 illustrate a simplified form of the novel hook member, which is intended more especially for ordinary curtains not provided with a heading; and the prong 35 of the wire portion 36 thereof is in this instance downwardly directed and at its other end is bent inwardly and then transversely to form a 90

95

100

- loop or eye constituting a stop member 37 to prevent dislodgment of the entire hook member when the same is attached to a curtain. Furthermore, the prong portion 35 will tend to coact with said stop member 37 to enhance the holding action. Similarly, as illustrated in Figs. 9 and 10, the prong 38 is downwardly directed and the opposite end of the wire length 39 is turned inwardly but provided with a cross-bar or rod 40 in place of the eye member 37 of the previously described embodiment.

- In attaching the modified type of hook member to a curtain as the curtain 41, Fig. 14 of the drawings, and which is adapted to slide upon a rod 42 by means of the curtain rings 43 having the eyes 44, a prong 35 or 38 is first forced inwardly in inverted position through the material, then brought forwardly through the same and through an eye 44 of a ring 43, whereupon the hook member is pulled forward sufficiently to bring its stop member, as the eye 37, against the corresponding face of the curtain, as shown. It will be understood, also, that the bent portion of these modified hooks is adapted for mounting directly over a rod, rather than causing the same to pass through an eye of a ring, etc.
- As illustrated in Figs. 11 and 12, the type of hook member shown in Figs. 1 to 3 may also be modified to ride directly upon a curtain rod or the like; and to this end it is formed with the single prong 45 and the wire length looped around to afford, for example, the elliptical closed loop 46 for fitting about a suitable rod.

- In the use of the foregoing hook members it will be appreciated that an especially useful result is achieved in being able to dispense with any permanent securing of the hook member to said material as by sewing, which has been the general practice heretofore. This also facilitates removal of a hook member; it being understood, however, that when in position said hook member is securely located against dislodgment.

I claim:

1. A drapery hanging device of the character set forth, comprising a wire shank portion having an entering prong offset therefrom and adapted to pass through a curtain to hold itself therein and afford hanging means for the curtain, and the opposite end of said device being provided with means to prevent withdrawal of the same from the curtain and comprising a transversely extending portion of the wire located between the shank and prong and adapted to retain the curtain between itself and the shank.
2. A drapery hanging device of the character set forth, comprising a wire shank portion having an entering prong offset therefrom and adapted to pass through a curtain to hold itself therein and afford hanging

means for the curtain, and the opposite end of said device being provided with means to prevent withdrawal of the same from the curtain and comprising a transversely extending portion of the wire located between the shank and prong, the prong continuing beyond the said extending portion which is adapted to retain the curtain between itself and the shank.

3. A drapery hanging device of the character set forth, comprising a wire shank portion having an entering prong offset therefrom and adapted to pass through a curtain to hold itself therein, and the opposite end of said device being provided with means to prevent withdrawal of the same from the curtain and comprising a transversely extending portion of the wire located between the shank and prong, the prong continuing beyond the said extending portion and bent away therefrom, and the said extending portion being adapted to retain the curtain between itself and the shank.

In testimony whereof I affix my signature.
DICKRAN M. SARKISIAN.
